Fig. 6

FIGURE 1 is a perspective view of a window operator incorporating my new design.

FIG. 2 is a top plan view of the operator.

FIG. 3 is an enlarged fragmentary side view of the handle portion of the operator.

FIG. 4 is a front elevational view of the operator.

FIG. 5 is a side elevational view of the operator, taken from the right of FIG. 4.

FIG. 6 is an enlarged sectional view taken along the line 6—6 in FIG. 2.

The characteristic feature of my design resides in the configuration of the casing for the operating mechanism and the mounting bracket portion of the casing.

I claim:

The ornamental design for a window operator, substantially as shown and described.
